UNITED STATES PATENT OFFICE.

RICHARD F. LEDEERER, OF NEW YORK, N. Y.

AIRSHIP.

1,358,453.

Specification of Letters Patent.

Patented Nov. 9, 1920.

Application filed December 26, 1919. Serial No. 347,581.

To all whom it may concern:

Be it known that I, RICHARD F. LEDEERER, citizen of the United States, and resident of New York city, in the county of New York and State of New York, have invented certain new and useful Improvements in Airships, of which the following is a specification.

This invention relates to airships.

10 One of the objects of my invention is to provide a powerful airship developing great speed and lifting power.

Another object of my invention is to provide an airship in which the thrust of lifting air created by propellers may be fully utilized.

Further objects of my invention are to provide a machine of this kind having a plurality of sets of variably arranged planes 20 and a plurality of sets of step-like disposed propelling means devised in such manner as to cause the air to travel and thrust against first the lower plane and gradually against the next higher plane until the highest plane 25 is reached. In this way the air performs its full duty as to the lifting of the airship. In addition there are provided longitudinal guiding air ducts giving the airship a greater stability in respect to keeping its 30 direction.

They constitute a roof-like structure unaffected by air currents which may strike the ship from either side.

The provisions of other air ducts formed 35 between a series of cargo and machinery carrying compartments is very important. These ducts, in front of which propellers are provided, serve for carrying compressed air, forced therein by the propellers, to the 40 rear of the airship. The air issuing from the rear of these ducts has a pushing effect while simultaneously creating a suction of partial vacuum into which, figuratively speaking, the airship is pulled.

45 For facilitating the starting or lifting of the airship and for "braking" the landing operation, vertically operable propelling means are provided.

The provision of auxiliary power plants, 50 aside from the individual power devices provided for each propeller, and means for facilitating the operation of the propellers by either of the power sources, is another object of my invention.

55 In order to decrease the resistance to air of the various parts of my airship, air di-

verting means are provided in connection with such air resisting parts.

Other and very important objects of my invention are to provide powerful propellers 60 of more than two blades and means for reinforcing and interconnecting the blades at or near their ends, and means for firmly lodging the heavy duty propeller shafts at both sides of the propeller.

Still further objects of my invention are to provide resilient landing and "braking" devices arranged intermediate between landing 65 wheels.

The foregoing and other objects will be 70 more fully apparent from the following description and the accompanying drawings, forming a part of this specification, in which:

Figure 1 represents a perspective view of 75 my device.

Fig. 2 is a semi-diagrammatical side elevation of same.

Fig. 3 is a diagrammatical view of same showing the arrangements of parts.

Fig. 4 is a detail view of a coupling device.

Fig. 5 is a detail view of a base bearing for a vertical propeller shaft.

Fig. 6 is a detail view showing the arrangement of power transmissions for a 85 propeller.

Fig. 7 is a front elevation of a "pulling" propeller.

Fig. 8 is a detail view of a lifting and 90 landing propeller.

Fig. 9 is a detail view of air diverting means.

Referring to the drawings, 1 designates the lowest front plane, beneath which the 95 lowest series of "pull" propellers is located. Above plane 1 is the intermediate front plane 2 and above this is the top plane 3 provided at both ends with ailerons 4, which of course may be arranged in any convenient manner and need not necessarily form a part of the top plane. Behind the front planes is a pair of shorter glide planes 5 and 6 facing substantially the centers of the spaces between the front plane series.

Adjacent to the planes 5 and 6 is the second 3-plane series, similar to the front planes, consisting of bottom plane 7, intermediate plane 8 and top plane 9 which is provided with ailerons 10 and 11.

The second series of pull-propellers is mounted between the bottom plane 7 and the

intermediate plane 8. Next to the second 3-plane series is again a shorter pair of glide-planes, comprising planes 12 and 13 which are at the same height with planes 5 and 6 and are consequently located opposite the spaces of the second 3-plane series.

The last 3-plane series again comprising a lower plane 14, an intermediate plane 15, and an upper plane 16 with ailerons 17, 10 forms the rear end of the airship's body. Between the top plane and intermediate plane the third pull-propeller series is stationed.

The lowest pull-propeller series comprises 15 four four-blade propellers 18, each of which is driven individually by engines or turbines 19 and which may be coupled at will with an auxiliary driving source 20 by means of a convenient power transmission indicated at 21.

Similarly arranged and driven are the 25 four propellers 22 of the intermediate pull-propeller series, which are also driven by individual motors 23 and which also may be operated in emergency by auxiliary power plants 24 and 25. The last series of pull-propellers comprises but three individually driven propellers 26.

In the rear and above the lowest plane 14 30 are provided two individually driven push-propellers 27.

The pull-propeller series 18, 22 and 26, are arranged in step-like relation to each other and cause the agitated air at this part 35 to travel from beneath and bear against planes 1, 5, 8, 13 and finally 16.

Thus the lifting properties of the air are fully utilized and increased until leaving the rear top plane 16.

40 In addition to the pull and push propeller series there are provided three horizontal lifting and landing propellers 28 of sufficient size and power to enable the airship to rise substantially vertically from the spot 45 and to "brake" the force of impact when the airship lands. They are operated by a permanent and auxiliary power source 29.

All propellers, drives and power plants are mounted upon the main frame work 30, 50 above which a platform 31 is placed and which is equipped with a railing 32.

At the front the platform is built out into three cockpits 33 provided with a glass enclosure and seats for the pilots, from which 55 the airship is operated and where observations may be made.

In the rear of the cockpits are three rows of cars 34, 35 and 36 serving as engine, passenger, and cargo spaces and which are 60 equipped at their front with wedge-shaped projections 37 for decreasing the air resistance.

The cars are divided into compartments leaving gangways 38 to provide access to the 65 different divisions of the cars. The center

row of cars 35 is extended at the rear, as indicated at 39, and serves as mechanics' operating and storage room.

Between the three car rows are two long ducts 40, in front of which are placed the 70 two center propellers of the lowest pull-propeller series 18. The air forcibly driven by these propellers through the ducts will form in front of the propellers a vacuum into which the airship is, so to speak, pulled 75 while the issuing air at the rear of the ducts will push the airship forward.

On top and at the rear of the mechanics' car 39 is placed a tail plane 41 adjacent to which are three sets of vertical rudders 42 80 and horizontal rudders 43 which are pivotally mounted upon a frame work 44. This frame work is held in place by and attached at its center to the rear end of car 39 and near its ends to girders 45 connected with 85 the main frame work 30 of the airship.

On top of planes 3, 9, and 16 are three longitudinal gable-shaped ducts 46 open at the front and rear which serve for permitting the air to pass therethrough. 90

Figuratively speaking the ducts cut into the air thus forming longitudinal guides for the airship, which are unaffected or only slightly affected by transverse currents which may strike the ship. 95

In the center duct are openings 47 in which the lifting and landing propellers 28 are mounted.

As said before the first two series of pull propellers have their own individual power 100 plants 19 and 23 while they may be also driven by auxiliary motors 20, 24 and 25.

For coupling the propeller shaft 48 with either the motor or the auxiliary power a clutch mechanism, shown in Fig. 4, is operated by handle 49. When the handle is turned in the direction of the arrow the clutch 50, coupling the propeller shaft with its individual engine, is disengaged while clutch 51 engages the belt pulley 52 driven 110 by the auxiliary motor.

In the position shown the pulley is at rest and in its bearings rotates the shaft 48 being driven by its engine 19.

The shaft 48, rotating with the hollow 115 clutch shaft 53 in bearing 54, is also guided in bearings 55 and 56 (Fig. 6) on both sides of the propeller. These bearings are mounted in a frame work 57 in order to give the propeller sufficient stability, since its 120 dimensions are huge.

In order to prevent any mishap to the propellers due to centrifugal force a reinforcing annular bar or ring 58 interconnects all four blades 59. 125

These blades are preferably made of broad inclined board or sheets and are attached at the hub by two reinforcing plates 60 (Fig. 7).

Similarly constructed are the lifting pro- 130

5 pellers 28 comprising four still larger blades 61 reinforced by ring 62 and plates 63. Their vertical shafts 64 are similarly guided at both top and bottom side of the propeller 10 in bearings 65 and 66 resting in an upper frame 67 and upon a lower frame 68, respectively. The lower portion of the shaft 64 is set into a bearing 69 above which a horizontal driving pulley 70 is keyed to the 15 shaft and is driven by a convenient transmission indicated at 71.

10 All bearings are equipped with anti-friction devices as shown in detail in Fig. 5. There are ball, cylindrical or conical bearing members 72, taking up the thrust of the weight, and similar means 73 taking up the side friction. There may be collars 74 attached to the shafts to still further lessen the side friction. Upon the bearing is preferably mounted an oil receiver 75 which again is provided with a dust proof cover 76.

15 The entire main structure of the airship rests, when at the ground, upon a plurality of landing wheels 77 arranged in such a way as to slightly give when the airship lands, thus permitting the brake-devices 78, arranged in the spaces between the wheels, to take up the shock and strain, and at the same time to plow themselves into the 20 ground.

25 The foregoing is only a general description of my device and it is understood that any details may be worked out in many different ways to suit special conditions.

30 35 In order to minimize the resistance of parts exposed to the air pressure while the airship is traveling at great speed, such parts or constructive details are either equipped with wedge-shaped shields as 40 shown in Fig. 9 or are built in such or similar form as indicated at 79 in Fig. 7.

45 Having thus described my invention in broad lines, and reserving for myself the right to make any alterations, changes or additions in its construction, what I wish to cover by Letters Patent and what I claim is:

50 1. An airship having a plurality of groups of planes consisting of three groups of three planes and two groups of two planes, said two-plane groups arranged intermediate between the three-plane groups, a group of four engines placed below the first three-plane group, another group of 55 four engines placed above the lowest plane of the center three-plane group and a group of three engines placed above the intermediate plane of the last three-plane group, and two end engines above the lowest plane 60 of the last three-plane group, triangular ducts disposed transversely to and above the plane groups and helicopters arranged within one of the ducts.

65 2. An airship having a plurality of sets

of planes, three sets, comprising three planes 65 arranged above each other, and two sets composed of two-planes, the three-plane sets disposed one at the front, one at the rear and one at substantially the center of the airship body, the two-plane sets arranged 70 intermediately between the three-plane sets, a group of power driven propellers in front and below the front plane set, another propeller group disposed above the lowest plane of the center plane set, a third propeller 75 group below the upper plane of the rear plane set, and a fourth propeller group above the lowest plane of said last plane set, triangular ducts disposed longitudinally with the airship body and above the plane sets, helicopters arranged within the center duct adapted to lift the airship in vertical direction.

80 85 3. An airship having three three-plane sets and two two-plane sets the latter arranged intermediately between the former, three groups of engine driven propellers associated with the three-plane sets and arranged in a step-like fashion, adapted to throw air from the lowest front plane to 90 the next higher plane of the adjacent plane set and subsequently to the highest rear plane.

95 4. An airship as set forth in claim 3, having a plurality of longitudinal air ducts arranged above its planes and helicopters provided within one of the ducts for the purpose described.

100 5. An airship having three three-plane sets and two two-plane sets arranged intermediately between the former, groups of motor driven propellers disposed intermediately between individual planes and the plane sets, air ducts above the planes, helicopters associated with one of the ducts, a 105 group of longitudinally disposed cars disposed below the planes, and having passages between them.

110 6. In combination with an airship as set forth in claim 5, propeller shaft supports arranged at both sides of the propellers.

115 7. In combination with an airship as set forth in claim 5, auxiliary power plants for driving said propellers when their individual motors become useless, and means for engaging said propellers with either their individual motors or the said auxiliary power plants, substantially as described.

120 8. In combination with an airship as set forth in claim 5, wedge-like extensions provided in front of said cars for the purpose and substantially as described.

125 9. An airship comprising three sets of planes composed of three individual planes, the top planes having ailerons, two sets of shorter planes comprising two individual planes arranged between the first sets, a balancing short single rear plane, three sets

of vertical and four sets of horizontal steering blades, three sets of step-like arranged pull propellers, one set of rear push propellers, lifting and landing propellers, 5 guide air ducts, propeller air ducts, arranged between three rows of compartments, a plurality of landing wheels and a plu-

rality of resilient landing brake devices arranged between said landing wheels.

Signed at New York city, in the county ¹⁰ of New York, and State of New York, this 27th day of October, A. D. 1919.

RICH. F. LEDERER.
